MOLDED FRUIT TRAY

Ronald A. Schelmetic, Fairfield, Conn., assignor to
Diamond International Corporation, New York,
N.Y., a corporation of Delaware

Filed Mar. 18, 1968, Ser. No. 11,003

Term of patent 14 years

(Cl. D9—187)

FIG. 1

FIG. 2

FIG. 3

FIG. 4

FIG. 5

FIG. 6

FIG. 1 is a top perspective view of a molded fruit tray showing my new design;

FIG. 2 is an enlarged top plan view of the molded fruit tray of FIG. 1, the bottom plan view of which generally following the same line form as the top plan view but being generally a reversed view thereof;

FIG. 3 is a side elevational view looking at the lower edge of FIG. 2, the opposite side being a duplicate of that shown;

FIG. 4 is a longitudinal section taken on the plane of line 4—4 of FIG. 2;

FIG. 5 is an end elevational view looking at one end of FIG. 2, the ends of the tray being duplicates; and

FIG. 6 is a transverse sectional view taken on the plane of line 6—6 of FIG. 2.

The characteristic feature of the present design resides in the combination, on a tray of the configuration shown, of an interior longitudinal partition rising to substantially

the height of the outer side walls and including transverse, spaced concave notches extending partially into the longitudinal partition, and triangular-appearing segments in the plane of the tray margin having arcuate sides diverging from the notches into flange-less side walls, substantially as shown.

I claim:

The ornamental design for a molded fruit tray, as shown and described.
